UNITED STATES PATENT OFFICE.

MELVIN T. MILES, OF CHEROKEE, IOWA, ASSIGNOR OF TWO-THIRDS TO
EDWARD O. LEWIS AND FRED S. JAMES, OF SAME PLACE.

COUPLING.

SPECIFICATION forming part of Letters Patent No. 565,770, dated August 11, 1896.

Application filed October 26, 1895. Serial No. 566,965. (No model.)

To all whom it may concern:

Be it known that I, MELVIN T. MILES, of Cherokee, in the county of Cherokee and State of Iowa, have invented a new and Improved 5 Coupling; of which the following is a full, clear, and exact description.

The invention relates to devices for conducting air, steam, and other fluid from one railway-car to another, and its object is to 10 provide a new and improved automatic coupling which is simple and durable in construction, very effective in operation, arranged to insure a positive connection without danger of leakage, and adapted to set the brakes in 15 case the train breaks in two.

The invention consists principally of a spring-pressed valve having a hollow body provided with a head and a stem having a longitudinal groove adapted to extend through 20 the valve-seat when a coupling is made.

The invention also consists of certain parts and details and combinations of the same, as will be fully described hereinafter, and then pointed out in the claims.

Reference is to be had to the accompanying drawings, forming a part of this specification, in which similar characters of reference indicate corresponding parts in all the figures.

Figure 1 is a side elevation of the improvement. Fig. 2 is a plan view of the same. Fig. 3 is a reduced front end elevation of the improvement. Fig. 4 is an enlarged sectional side elevation of the valve-head with the 35 valve in an open position. Fig. 5 is a similar view of the same with the valve in a closed position. Fig. 6 is a perspective view of the valve, and Fig. 7 is a cross-section of the same on the line 7 7 of Fig. 6.

The improved coupling is provided with a head or casing A, secured to the forward end of a pipe B held in hangers C and D, secured to the under side of the car E, as indicated in Figs. 1 and 3. The rear end of the pipe 40 B is provided with an elbow B', connected by a piece of hose B² with a T of the train-pipe F, extending under the car. A spring B² is coiled on the rear end of the pipe B and rests with one end on the hanger D and with its 45 other end presses on a collar B³ secured on the pipe B. The spring B² yields sufficiently

when the cars are coupled and also compensates for any slack when the cars are going around curves. The hanger D is rigid on the car E, while the hanger C is provided on its 55 upper end with a grooved pulley C', mounted to travel on a segment C² secured to the under side of the car, so that the pipe B, with the head A, can swing to the right or to the left when the cars are going around curves, 60 and the hanger C can be swung to one side when it is not desired to couple the two train-pipes of the adjacent car.

The head A is provided with two bores A' and A² separated one from the other by a 65 valve-seat A³, the bore A² opening into the pipe B. In the other bore A' is fitted to slide a hollow valve G, passing through a stuffing-box H held on the front end of the head A, and on the outer end of said valve G is formed 70 a curved projection G', carrying a rubber gasket G² adapted to be engaged by a like gasket on a slide-valve G held in the head A on the car to be coupled.

On the inner end of the valve G is formed 75 a stem G³ fitted to slide in the valve-seat A³ and provided with one or more longitudinally-extending grooves G⁴, so that when the valve G is pressed inward into the position shown in Fig. 4, then the groove G⁴ connects the 80 bore A² with the bore A', so as to allow the air, steam, or other fluid from the train-pipe F, and passing through the pipe B, to pass into the bore A' and through the hollow valve G to the corresponding valve in the head on the 85 adjacent car to conduct the fluid from one car to the other.

On the valve-stem G³ is coiled a spring I, resting with one end on the valve-seat A³ and with its other end on the shoulder formed at 90 the junction of the stem G³ with the valve G. This spring I normally holds the valve G in an outermost position, as shown in Fig. 5, so that a valve-disk G⁵ is seated on the seat A³ to normally close the said valve A³. The 95 disk G⁵ is held in place by a washer G⁶ and a nut G⁷, screwing on a reduced end G⁸ of the valve-stem G. Now, when two cars come together, the valves G are pressed inward against the tension of the spring I, so that the 100 valve-disks G⁵ are unseated and communication is established between the bores A² and

A' by the grooves G⁴ in the valve-stems, as previously explained, to permit the fluid to pass from one car to the other. The projection G' is formed with an angular groove G⁹, 5 adapted to be engaged by a hook J, fulcrumed at J' on the head A. The hook J is used to engage the groove G⁹ when it is desired to hold the valve G open so that the air within the train-pipe B may be exhausted to permit 10 the brakes to set when two cars become accidentally disconnected. When it is desired that the valve G be closed, the hook J should be disengaged from the groove G⁹, thereby permitting the valve to retain the proper 15 pressure within the train-pipe.

In order to insure a perfect coupling I provide each head A on one side with a fixed plate K and with a spring-plate L, having an offset L', adapted to engage a recess A⁴ in the 20 side of the head A on the adjacent car, it being understood that the said recess A⁴ is on the side opposite to where the plates K and L are fastened. (See Fig. 2.) Thus when 25 two cars come together the offsets L' of the spring-plates snap into the recess A⁴, so as to hold the two heads in a coupled position and at the same time make connection between the two valves G, so as to establish communication between the train-pipes of the 30 adjacent cars. Now it will be seen that in case a train breaks in two the heads A readily uncouple by the projections A' disengaging the recess A⁴.

It will further be seen that when two cars 35 are uncoupled the spring I forces the valves G outward to seat the valve-disks G⁵ on the seats A³, thus disconnecting the bores A² and A' of the coupled heads A.

Having thus fully described my invention, I claim as new and desire to secure by Letters 40 Patent—

1. In a hose-coupling, the combination with a head having two longitudinal bores divided by an inwardly-extended valve-seat, a valve longitudinally movable in the bores, 45 the valve having a hollow portion and having recesses formed in one end, a plate held adjacent to said recessed end and capable of bearing against the valve-seat, a spring engaging the valve and tending to move said 50 plate on the valve-seat, and a spring-plate carried by the head and capable of engagement with a companion head, substantially as described.

2. In a hose-coupling the combination of a 55 head having a longitudinal bore provided with a valve-seat, a valve longitudinally movable in the bore, the valve having a reduced and partially-recessed stem sliding through the valve-seat and having an enlarged hollow 60 portion outward from the stem, said enlarged hollow portion having a groove, a plate carried by the stem and adapted to engage the valve-seat, a spring embracing the stem and contained within the bore, said spring tending 65 to move the valve so that the plate will be pressed against the valve-seat, a hook pivotally mounted on the head and adapted to engage the groove on the enlarged hollow portion of the valve, and a spring-plate carried by the head, substantially as described. 70

MELVIN T. MILES.
